Des. 241,352
Patented Sept. 7, 1976

241,352

ELECTRICAL PLUG

Higinia Acosta, 332 E. 14th St.,
New York, N.Y. 10003

Filed Oct. 16, 1975, Ser. No. 623,862

Term of patent 14 years

Int. Cl. D13—03

U.S. Cl. D26—1 B

FIG. 1 is a side elevational view of an electrical plug showing my new design.

FIG. 2 is a view looking from the top of FIG. 1.

FIG. 3 is a view looking from the left side of FIG. 2, and

FIG. 4 is a view looking from the right side of FIG. 2.

I claim:

The ornamental design for an electrical plug, as shown.
